UNITED STATES PATENT OFFICE

2,512,560

RADIATOR HEADER CONSTRUCTION

Fred M. Young, Racine, Wis., assignor to Young
Radiator Company, Racine, Wis., a corporation
of Wisconsin

Application August 7, 1946; Serial No. 689,018

1 Claim. (Cl. 257—125)

1

This invention relates to headers for heat-exchange devices and the method of forming the same.

In the construction of larger size heat-exchange devices, for use with fluids required to dissipate the heat created by large, high-powered equipment, it is the practice to fabricate the heat-transfer section for such a device from a plurality of separately-formed core units, each unit being individually assembled on a tank to constitute a completed heat-exchange device.

Each of the several core units is a fabrication of sheet metal tubes extending through a bank of thin metal fins with the ends of the tubes extending through and bonded to header plates. Headers are then secured to the header plates which headers are clamped to the tanks to afford fluid communication between the tubes of the several core units and the tanks for the circulation of the coolant.

The magnitude of the tank required for large size devices makes casting the only practical alternative to any other method of producing it. Heretofore it has always been the practice to cast also the headers by which the several core units were attached to the tank. However, this has presented a number of problems. The headers being small and light-weight, compared with the tank, difficulties have been encountered in forming these headers by foundry practices designed for heavier constructions. On the other hand, cast headers are poor conductors of heat. Also, there is no assurance of uniform thickness of the metal, which means an uneven heat transfer. Moreover, cast metal has a certain porosity which, with constructions of this type, presents the hazard of some leakage of the fluid used as a coolant.

In addition to the foregoing difficulties there is the item of expense incurred in machining and of tin or alloy coating of the interior surfaces of such castings.

The main objects of this invention, therefore, are to provide an improved construction and method of producing headers for use in securing separately-fabricated core units in fluid communication with the tank of a large heat-exchange device; to provide improved construction and method of producing these separately-formed headers from sheet metal formations; and to provide improved means for attaching headers of this type to the tank.

A preferred embodiment of this invention is shown in the accompanying drawings, wherein:

Fig. 1 is a front elevation of a relatively large

2

heat-exchange device wherewith headers, constructed in accordance with this invention, are especially adapted for use in fabricating such a device;

Fig. 2 is an enlarged, perspective, and partly sectional view of a header embodying this invention shown attached to one end of one of the core units employed in fabricating a heat-exchange device shown in Fig. 1;

Figs. 3, 4, and 5 are perspective views of the three sheet-metal stampings which are fusion bonded together to form the improved header shown in the other views; and

Fig. 6 is a side elevation of this improved header formed of the three aforesaid sheet-metal stampings, shown in association with the clamping means by which such headers are preferably secured in position on the fabricated device shown in Fig. 1.

20 A heat-exchange device, of the type wherewith headers involving this invention have been designed for use, comprises a tank 7 to which a plurality of separate core units 8 are connected by means of these improved headers 9 through the use of clamping means 10. Such a heat-exchange device is designed for use with coolants required in the dissipation of heat generated by heavy-duty machinery, as, for example, large trucks, tractors, earth-moving machinery, air compressors, Diesel-powered locomotives, and condensing towers. To have the required heat-exchange capacity such devices often are five, ten, and twelve feet in height or length. They have to be constructed to withstand high pressures, and 35 when used on mobile units must be able to withstand much vibration and shock. It is imperative, therefore, that the various parts be rigidly constructed and firmly assembled.

The tank 7, which, obviously, is quite a sizable unit, is cast metal or fabricated sheet steel. It is formed with a coolant chamber which, through suitable inlet and outlet ports (not herein shown), is connected in a coolant-flow circuit with a heat-producing machine and a source of coolant supply.

30 The core units 8, of more or less conventional construction, each comprises a plurality of tubes 11, herein shown to be of flat form, the ends of which extend through and are bonded to header plates 12 and on which, between the header plates 12, are mounted a plurality of closely-spaced, thin, metal, heat-dissipating fins 13. Other plates 14 are secured at opposite sides of such an assembly to form a passage for fluid, generally 45 air, around and between the tubes 11 and fins 13,

which fluid is thus brought into heat-exchange relationship with the coolant flowing through the tubes 11. Each header plate 12 is formed with a perimetrical flange 15 which interfits and is bonded to the header 9.

Headers 9 constructed in accordance with this invention each comprises three separately-produced sheet-metal formations, a base 9A, a standard 9B, and a cowl-like element 9C, which are subsequently bonded in assembled relationship to provide an attachment for securing the core units 8 to the tank 7 and providing fluid communication between the ends of the tubes 12 and the chamber in the tank 7.

The base 9A is formed with an opening 17 and a perimetrical flange 18. The flange 18, in addition to contributing rigidity to the base 9A, has interfitting engagement with the perimetrical flange 15 on a header plate 12, which flanges are bonded together, and thereby forming a chamber between the header plate 12 and base 9A affording communication between the ends of the tubes 11 extending through the header plate 12 and the opening 17 in the base 9A.

The standard 9B is formed with an opening 19 which is adapted to register with a comparable opening in the tank 7 when the headers 9 are clamped to the tank 1 to secure the heat-exchange units 8 in assembled functioning relationship therewith.

The cowl-like element 9C is formed with outwardly-extending flanges 20 and 21 along the right-angularly-disposed perimeters, the flange 21 being adapted to rest upon the base 9A and encircle three sides of the opening 17, whereas the flange 20 is adapted to contact the face of the standard 9B around the top of the opening 19 and along the edges of the part 9, divergently downward from the opening. The cowl 9 thus constitutes a conduit for fluid flow through the openings 17 and 19 between the ends of the tubes 11 and the chamber in the tank 7. The cowl-like element 9C also has formed a pad-like bulge 22 on the back thereof with which co-acts the clamping means 10 for securing a header 9 in fluid-tight contact with the tank 7.

The clamping means 10 comprises bars 23, which are held in place by nuts 24 on stud bolts 25. The bars 23, as shown herein, are preferably of U-shaped form such that the ends of the parallel parts of the U fit over the pads 22 on adjacent headers, as clearly shown in Fig. 1. By means of the nuts 24, on stud bolts 25 anchored to the tank 7, intermediate each pair of headers 9, the standard 9B of each header 9 is held in fluid-tight contact with the tank 7.

The method of forming and assembling this three-piece metal-stamping header is more or

less apparent from the foregoing description. After the formations have been separately produced the standard 9A is placed upright on the base 19 along one edge of the opening 17, preferably the straight edge as shown in Fig. 3. The parts are then suitably bonded together by brazing or welding. Subsequently the cowl-like element 9C is placed on the base with the flange 21 extending around the three other sides of the opening 17 and with the flange 20 resting up against the face of the standard 9B. These parts are then bonded together by brazing or welding.

Variations and modifications in the details of structure and arrangement of the parts may be resorted to within the spirit and coverage of the appended claim.

I claim:

A heat-exchange header fabricated from a separately-formed sheet-metal base having the perimetrical portion up set to provide a reinforcing flange for telescopically fitting a heat exchange core header plate and having an opening formed in the flat part, one side of which opening is straight and parallel to one edge of said base and the other side of which opening is arcuate-shaped, a metal plate standard likewise having an opening therein, and a sheet-metal cowl-like element having its perimeter outwardly flanged and disposed in two planes at right angles to each other, all bonded together with said standard disposed perpendicularly on said base along the straight edge of said base opening and with the right-angularly-disposed perimetrical flanges of said cowl-like element respectively abutting the right-angularly-disposed faces of said assembled base and standard so as to provide an arcuate conduit connecting the openings in said base and standard.
